Patented May 3, 1960

187,840

COMBINED LIPSTICK HOLDER AND VANITY CASE

Leon H. Levi, Beverly Hills, Calif., assignor to Max Factor & Co., Los Angeles, Calif., a corporation of Delaware

Application August 4, 1958, Serial No. 52,017

Term of patent 14 years

(Cl. D86—10)

FIG. 1.

FIG. 2.

FIG. 3.

FIG. 4.

FIG. 5.

Fig. 1 is a front perspective view of a combined lipstick holder and vanity case showing my new design;

Fig. 2 is a front elevational view thereof;

Fig. 3 is a top plan view;

Fig. 4 is an end elevational view as seen from the right of Fig. 3; and

Fig. 5 is an end elevational view thereof as seen from the left of Fig. 3.

The top and bottom of the container are flat and have no ornamentation thereon.

I claim:

The ornamental design for a combined lipstick holder and vanity case, as shown and described.
